BOBBY PIN SETTER

Felix Redo, New London, Conn.

Application April 13, 1951, Serial No. 220,824

10 Claims. (CL. 132—11)

1

The invention relates to a bobby pin setter. In styling a woman's hair bobby pins are frequently used. The conventional way of applying a bobby pin properly requires the following operations: A narrow strand of hair is parted off e. g. with the tail end of a rat tail comb held taut and combed smooth whereupon the comb is laid down and the strand is wound around the index finger of the hand originally holding the comb or the strand is wound around the tail end of the comb which, then, is laid down. Thereafter, while the one hand holds the curl in place, a bobby pin is picked up, opened with the finger nails or mostly with the teeth and finally applied to the curl. This conventional procedure is objectionable for the main reason that frequently the fingernails are broken or the teeth are injured in opening the pin, i. e. in the spreading apart of the strongly resilient pin legs. Furthermore, the steps of preparing the pins for application and the laying down of the comb and taking it up again are time consuming, and the loss of time so caused is quite noticeable if it is considered that frequently up to sixty and in quite a number of cases many more pins are required to style the hair as desired.

The invention aims to provide a device whereby the mentioned drawbacks can be avoided. The invention also aims to provide a device whereby the required manipulations of a bobby pin can be accomplished with one of the user's hands. The invention essentially consists of a setting means with the aid of which a bobby pin can be picked up, held with its legs spread apart, then, applied to the user's hair in a desired position, and finally released when in the desired position. The invention further contemplates the provision of means to hold a plurality of bobby pins in such a manner that one after the other can be readily picked up by the first mentioned means.

In the preferred form of the invention the pin setter is combined with a rat tail comb, whereby the preparation of the hair for the setting of the pin as well as its application can be accomplished with one instrumentality, and the parts of the combination are in such relationship to one another that all manipulations can be accomplished without a change of the user's grip on the device.

Further objects and details of the invention will be apparent from the description given hereinafter and the accompanying drawing illustrating an embodiment thereof by way of example. In the drawing,

Fig. 1 is a top plan view of a bobby pin setter according to the invention in combination with a rat tail comb,

Figs. 2 and 3 are a side elevation and a bottom plan view thereof, respectively, parts being broken away;

Fig. 4 is a cross-section along line 4—4 in Fig. 1;

Fig. 5 is a top plan view of a pin rack for use with the setter part;

Fig. 6 is a cross-section along line 6—6 of Fig. 5;

Fig. 7 is a top plan view of a rack holder;

Fig. 8 is a cross-section along line 8—8 of Fig. 7;

Fig. 9 is a top plan view of the rack of Fig. 5 positioned in the holder of Fig. 7;

Fig. 10 is a partial cross-section along line 10—10 of Fig. 9;

Figs. 11, 12 and 13 illustrate the picking up of a bobby pin in three different stages;

Fig. 14 illustrates the releasing of a pin from the setter;

Fig. 15 is a top plan view of a modified setter and

Fig. 16 is a top plan view of modified pin rack.

Referring now to the drawing, Figs. 1 to 4 show the bobby pin setting device in combination with a comb 1 of a type conventionally used

in order to apply bobby pins to the hair. The comb has the toothed portion 2 and a rat tail portion 3. From the back of the comb, approximately where the toothed part 2 and the tail 3 meet, a flat body portion 4 extends substantially at right angles to the plane of the comb. Body 4 of the illustrated embodiment is of L-shape but may be of any other suitable configuration. Its lower edge is recessed at 5 near one of its ends so as to form a hook-like projection 6 with its tongue 7 facing another substantially flat projection 8 which constitutes an abutment for a purpose to be explained hereinafter. Another hook 9 is movably attached to the body 4. The tongue 10 of hook 9 is directed towards the abutment 8, and the hook has a pivot at 11 at a point between the comb 1 and abutment 8; that means, when the flat body 4 is held with the abutment downward, a point above the abutment and between the latter and the opening of the hook 9 so that the hook 9 to swing towards

the latter owing to its gravity and that it will turn in the opposite direction if pressure is exerted on its tongue 10 from below. Means are provided to prevent the hook 9 from turning in a clockwise direction in Fig. 2 beyond a point at which tongue 10 is on a level somewhat higher than that of the abutment 8. For this purpose, the pivoted hook portion 12 is forked, so that further downward movement of the hook is stopped when the fork bottom 13 bears against

the edge 14 of body 4 as in Fig. 2. Hook 9 is furthermore, provided with a little projection 15 which extends in the direction of the comb teeth and serves as a grip for the user's finger in order to lift hook 9. The inside of tongue 10 is provided with a shallow groove 16 of a width ac-

cording to that of a bobby pin for which the setter is destined. A groove 17 of the same width is provided in the lower face of abutment 8. This groove preferably increases in depth in the direction of hook 6. The tongue 7 of the latter is also grooved at 18 and at its tip is slightly recessed at 19 so that the flanks of the recess, in a sense, constitute guide rails leading into the groove 18.

The bobby pin setter of Figs. 1 to 4 is useful to pick up a bobby pin to hold it with its legs spread apart, and to release it when applied to the hair. Although it is possible to use the setter by placing the head of the pin into the recess 5 of the hook 6 and bending the one pin leg so that it bears against the abutment 8 and its end is engaged by hook 9, the full utility of the setter can be enjoyed in combination with a means which is also part of the invention and which so holds the bobby pin that it can be readily picked up by the setter in a semi-automatic manner. Such device is illustrated in Figs. 5 to 10 and will now be described.

The device is designed as a rack in general denoted by 20, which has a flat base 21 of substantially rectangular shape. An upwardly protruding ledge 22 along one of the sides of the rectangle is either integral with or secured to the base 21. The ends of the ledge may be spaced a short distance from the adjacent sides of the base as shown at 23 and 24. A ramp 25 of short height and slight inclination projects from the ledge forward, i. e. towards the opposite edge 26 of the base. The top surface of the latter is provided with a plurality of grooves 27, for instance twenty according to the number of bobby pins 28 the rack is intended to accommodate. Very close to ramp 25, the bottoms of the grooves gradually rise to the top surface of the foot of the ramp. The depth and width of the grooves 27 are selected according to the dimensions of the lower leg 29 of a bobby pin, i. e. that leg which is supposed to be applied to the user's hair, and the distance from the front edge 26 to the ledge 22 should be so selected that a pin 28 in the position of Fig. 6 projects with its loop or head portion 30 forward from the edge 26. As mentioned hereinbefore the ledge 22 need not extend the whole width of the rack base. However, it should extend opposite the ends of all the grooves 27. Parallel to ledge 22 a bar 31 having an inclined front flank 32 is secured to base 21 at a short distance from the foot of the ramp 25, so that the bar bridges the grooves 27.

Now, it will be clear that for charging the rack, each bobby pin 28 can be shifted in a groove 27 with its lower leg 29 underneath bar 31 while the upper pin leg 33 will be raised by the inclined flank 32. When the end of the lower leg has passed the bar it will be slightly lifted by the ramp 25 until it finally abuts against the ledge 22. This is the position shown in Fig. 6 in which the legs 29 and 33 are spread slightly apart and the end 34 of the upper leg projects rearwardly beyond the bar 31. It will be noticed that the ramp 25 causes a slight upward bend of the end 35 of the lower leg 29. This is desirable in order to insure that the pin portion adjacent the head 30 is firmly located in the coordinate groove 27.

Means are preferably provided to clamp the rack 20 so to the top board of a dressing table that it cannot be readily shifted in the direction of the grooves 27. A rack holder for that

purpose is shown in Figs. 7 and 8 which is of such a design that a rack can be readily exchanged for another one. The holder in general denoted by 40 comprises a plate 41 with an upwardly projecting rim 42 along its rear edge, and with another rim 43 along its front edge. The front rim is preferably a little lower than the thickness of the rack base 21 in order not to interfere with the heads of the bobby pin when the rack edge 26 bears against the rim 43. A leaf spring 44 is secured to the rim 42 and projects with its bight towards the front rim of the plate 41 which is approximately of the same width as but somewhat longer than the rack 20. The front corners of the plate 41 are provided with small flange pieces 45 and 46 to form short channels 47 and 48 of a height according to the thickness of the rack base 21. From the middle of the front of plate 41 a resilient hook-shaped extension 49 projects by means of which the holder can be clamped to a table board.

In order to apply a rack to the holder, the rack will be placed with its rear edge against the spring 44 and then, pushed back against the tension of the spring until the front corners 50 and 51 which for this purpose may be rounded, can slide forward into the channels 47 and 48, respectively. In order to facilitate the application of the rack to the holder the latter may be provided with lateral recesses 52 and 53, and the rack may have corresponding projections 54 and 55 serving as finger grips. Figs. 9 and 10 show the rack 20 applied. It is, of course, possible to make the clamping means integral with a rack as shown in Fig. 16. In this modification the rack 120 is similar to the rack 20, except that it is provided with a clamping hook 149 of the kind of hook 49 of the holder 40. However, I have found it preferable to make the rack and the holder as separate pieces since the space required for one holder and a plurality of racks without clamps is smaller than the same number of racks with integral clamps.

The bobby pin setter in combination with the rack will be used in the following manner: The rack charged with bobby pins will be clamped in position. After a strand of hair has been combed and curled as hereinbefore described, the curl is held with the one hand while the user's other hand holding the comb with the setter downward, applies the latter so that the hook 6 engages the head 30 of a bobby pin 28 as shown in Fig. 11. The recess 19 and groove 18 of the hook tongue 7 facilitate the proper locating of the pin head. It will be noticed that the corner of abutment 8 adjacent hook 6 bears on top of the upper pin leg 33 which engages the groove 17. Now the setter is turned about that corner in a clock-wise direction, thereby the head portion of the pin will be bent upward and the tongue 10 of the pivoted hook 9 will come to bear on top of the end 34 of the upper pin leg. When turning of the device in the stated manner is continued, pressure by the leg end 34 acting on hook 9 will turn the latter about its pivot 11 in a counter-clockwise direction until the tongue 10 has cleared the leg end 34 whereupon hook 9 owing to gravity will drop down to catch the end 34 from its lower side. This position is that of Fig. 12. The bobby pin is now firmly gripped. By pulling the setter in the direction of the pin head, the pin can be withdrawn from the rack. If this is done all bending stress on the lower pin leg 29 is relieved so that it straightens out whereas the upper pin

leg 33 is strongly bent owing to the fact that the abutment 8 projects from the connecting line of the points where the head and the end of leg 33 are supported. Thus, the legs of the pin held by the setter are widely spread apart as illustrated in Fig. 13. In this position, the pin is slid with its lower leg underneath the curl or strand of hair, the setter being held as shown in Fig. 14. When the pin is properly placed, thumb pressure on the projection 15 from below will release the hook 9 from holding position so that the upper leg 33 will snap down to clamp the curl or strand against the lower pin leg. Simultaneously, the pin will be freed from the setter, and the whole procedure can be repeated with another pin until all bobby pins are set. When the pins of one rack are exhausted another rack can be attached to the holder within a minimum of time. Tests have shown that with the aid of the device according to my invention bobby pins can be properly set without the risk of one's breaking finger nails or injuring teeth, in less than half the time conventionally required so that a great saving of time can be made if a large number of pins are needed for a desired hair styling.

In the embodiment of my invention hereinbefore described, the setter has been shown in combination with a rat tail comb, as I have found that in such combination the advantages of my invention can be realized to their fullest extent. However, it will be clear that the setter may also be advantageously used if combined with another type of comb or even separate from any comb. In any event, however, I have found it to be advisable that whatever hand grip is provided, such grip should be in a plane substantially at right angles to the setter body. As an example Fig. 15 shows the setter body 100 which is of the same design as body 4 in the preceding figures, with a flat handle 101 in a plane at right angles thereto.

Many alterations and modifications of the structure shown and described will be apparent to those skilled in the art and may be made without departure from the essence and spirit of my invention which for that reason shall not be limited but by the scope of the appended claims.

I claim:

1. A bobby pin setter comprising a substantially flat body having an edge recessed to receive therein the head of a bobby pin and to support said head on the side of one of the legs of said pin an abutment projecting from said edge and engageable by the other pin leg between its free end and said head, and a hook pivoted to said body so as to rock in the plane thereof and being adapted to grip the end of said other leg of said pin releasably and to hold said other leg against said abutment and bent away from the first mentioned leg of said pin when said head is engaged in said recess.

2. A bobby pin setter comprising a body including a first hook-like projection adapted to receive therein the head of a bobby pin, and another projection constituting an abutment, said abutment being spaced from said hook-like projection on the side of the opening thereof and being adapted to bear on the adjacent leg of said pin intermediate said head and the free leg end when the said head is located in said hook-like projection, and a second hook-like member movably attached to said body and adapted to grip said free

end of said leg and to hold said leg bent away by said first hook-like projection and said abutment.

3. A device as claimed in claim 1, said movable hook including a grip portion for the user to release said movable hook from its holding position.

4. A device as claimed in claim 2, comprising two substantially flat portions in planes, respectively, at a right angle to each other, said first hook-like projection and said abutment being integral with one of said portions which constitutes said body, and said other portion constituting a handle.

15 5. A device as claimed in claim 2, said movable hook-like member being pivoted to said body at a point which, when said device is held with said abutment downward, is located above said abutment and between said abutment and the opening of said movable hook-like member whereby

20 said movable hook-like member has the tendency of turning towards said downwardly held abutment, and of turning in the opposite direction when pressure is exerted on the tongue of said movable hook-like member from below.

25 6. A device as claimed in claim 2 wherein the inside of the tongue of the hook-like projection and the edge of said abutment are grooved to receive in said grooves said pin head and said adjacent leg, respectively.

30 7. A device as claimed in claim 2, wherein the inside of the tongue of said hook-like projection is grooved to receive said pin head in said groove and the tip of said tongue is recessed so that the 35 flanks of said recess are adapted to guide the head of said pin into said groove.

35 8. A rack for a plurality of bobby pins in positions so as to be picked up by a setting device, comprising a flat substantially rectangular base 40 including a ledge projecting from the top surface along one of its sides, the width of the base between said ledge and the opposite side being shorter than a bobby pin for which the rack is destined, a ramp of small height and slight inclination extending from said ledge a short distance towards said opposite side, said base being provided with a plurality of parallel grooves extending from said opposite side of said base to the foot of said ramp and being of a depth according to the thickness of one leg of one of said 45 bobby pins, a bar parallel to said ledge and secured to said base a short distance from the foot of said ramp, said bar having an inclined flank facing said opposite side.

50 55 9. A rack as claimed in claim 8, said rack further comprising a clamping means in connection with said base to secure said rack to a table plate.

10 10. A rack as claimed in claim 8, further comprising a holder including a clamping means to 60 secure said holder to a table plate, said base being releasably attached to said holder.

FELIX REDO.
